PIANO

Louis C. Kauling, Kew Gardens, N. Y.

Application August 4, 1937, Serial No. 157,340

2 Claims. (Cl. 84—197)

This invention is directed to new and useful improvements in low height upright pianos and more particularly to such types of pianos having an overall height of about thirty-six inches.

5 The present trend of upright piano demand has been for such pianos of much lower height than those heretofore manufactured so as to reduce the room space necessary for such pianos. In reducing the height of the pianos the length 10 of the strings and the height of the sounding board must be reduced and the general mechanism of the piano which is operated by the keys must be lowered. The shortening of the strings and the reduction in size of the sounding board 15 sacrifices quality in the resultant tone.

Heretofore, in the construction of such pianos the piano plate, which is cast as a unit, extends vertically in the piano and is provided at its upper end with the tuning pins to which the 20 strings of the piano are secured.

The playing portion of the piano strings extends from the hitch-pins at the bottom of the plate to the V-bar, spaced somewhat below the upper end of the plate. From the V-bar to the 25 tuning pin is the non-playing portion of the piano strings which varies from three to five inches in length.

In reducing the general height of the piano it is apparent that the keyboard cannot be lowered proportionately. It must be maintained in 30 a more or less standard plane to facilitate the operation or playing of the piano.

Because of this fact the modern low upright pianos have been constructed with what is known 35 in the trade as "drop action". This means that the mechanism that is actuated by pressure on the piano keys to produce the musical tones has been lowered to extend below the keyboard to fit into the reduced height of the piano casing.

40 In dropping this mechanism below the plane of the keyboard to effect the so-called "drop action", the keys have been operably connected with the lower piano mechanism by means of wires or small cables. Thus when a piano key 45 is depressed to strike a note the inner end of the key is lifted and by means of a wire connecting the inner end of the key with a lever, positioned below the keyboard the general piano mechanism is actuated through its various levers and springs to cause the hammer to strike the 50 string and produce the desired note.

Aside from the fact that the tone quality is sacrificed because of the shortened piano strings, this "drop action" is undesirable because power 55

and repetition is sacrificed through the cable or wire connections.

In upright pianos of usual height there is a direct blow action between the inner end of the piano key and the lever that sets in motion the 5 various springs and levers to move the damper from the string, cause the hammer to strike the string, and at once leave the string by means of the escapement mechanism.

The primary object of this invention is to provide 10 an upright piano of low height in which the length of the piano strings is materially greater than those of pianos of similar height and in which the direct blow action is maintained thus obtaining superior tone quality and 15 flexibility in operation.

A further object is to provide such a piano 20 that will stay in tune longer than present pianos of similar size.

A still further object is to provide such a piano 20 with a cast piano plate adapted to receive the playing portion of the piano strings in vertical position and the non-playing portions in substantial horizontal position and secured to tuning pins vertically positioned in the upper portion 25 of the plate.

Another object is to provide such a plate having a lug cast integrally with it to support the key bottom to prevent its sagging.

Still further objects and advantages will be 30 apparent from the following detailed description.

In the drawing the figure shows a vertical cross-section view partially broken away of the working mechanism of a piano constructed in 35 accordance with this invention.

In detail, 1 indicates a cast metal piano plate comprising a vertical portion 2 that extends substantially the height of the piano and a horizontally extending portion 3. Positioned through 40 the horizontal portion 3 of the piano plate is a tuning pin 4 that extends into the tuning pin block 4a that is fitted immediately under the horizontal portion. Pressure bar 5 and beads 6 and 7 are secured to the top portion 3. The 45 V-bar 8 extends across the upper portion of the vertical surface of the plate adjacent the horizontal portion. Considerably below the V-bar and cast integrally with the plate is a key bottom supporting lug 9. The hammer operating mechanism is shown generally and comprises the hammer 10, damper 11, and the various levers and 50 springs which effect the operation of the hammer and its associated members.

Inasmuch as the operating mechanism affords 55

no part of this invention, further detailed description of it is not made.

The key bottom 12 is shown supported at its inner end by the lug 9 and fulcrumed on the key bottom 12 is the key 13, the inner end 14 of which extends beneath and is in direct contact with lever 15, so that upon depression of the outer end of key 13 the usual levers and springs are set in motion to move the damper 11 away from the string, cause the hammer to strike the string and release. The string 16 is shown extending vertically from hitch-pin 17 over bridge 18 parallel to the piano plate 1 over the V-bar 8 and horizontally over the beads 6 and 7 underneath the pressure bar 5 and secured to the tuning pin 4. The sounding board 19 extends parallel to the vertical portion 2 of the plate and supports the bridge 18 that extends through the plate 1. Thus it will be clearly seen that only the playing portions of the strings are carried by the vertical portion of the plate while the non-playing portions are led over the top parallel to the horizontal portion of the plate thus diminishing the height of the plate. In this manner three to five inches in vertical height of the piano can be saved without shortening the strings and without necessitating the installation of the so-called "drop action" mechanism.

Thus it can be clearly seen that by utilizing this invention a thirty-six inch piano can be produced that will have the tone and playing qualities of a thirty-nine or forty inch piano of the old type. Thus is obtained a popular small size piano without the undesirable characteristics of smaller sounding board, shortened strings and "drop action".

Furthermore by placing the non-playing portions of the piano strings at right angles to the

playing portions greater friction is produced between the strings, the V-bar and the beads thus reducing the strain and pull on the tuning pins. In this manner the piano maintains its tune much longer than if there was a direct pull on the pins. 5

I claim:

1. An upright piano of about three feet in height comprising a piano plate having a vertical portion extending substantially the height of the piano, a horizontal portion extending from the upper end of the vertical portion, a grand piano tuning pin block supported against the under surface of said horizontal portion, tuning pins extending through said horizontal portion and into the pin block, a string supporting V-bar 15 positioned on the vertical portion of the plate in substantially the same plane as the horizontal portion, and strings extending substantially the length of the vertical portion over the V-bar and closely adjacent the horizontal portion to the tuning pins. 20

2. An upright piano of about three feet in height comprising a cast metal piano plate having a vertical portion extending substantially the height of the piano, a horizontal portion extending from the upper end of the vertical portion, a grand piano tuning pin block secured to the under surface of said horizontal portion, tuning pins extending through said horizontal portion and into the pin block, a string supporting V-bar 30 positioned on the vertical portion of the plate in substantially the same plane as the horizontal portion and strings extending substantially the length of the vertical portion over the V-bar and closely adjacent the horizontal portion to the tuning pins. 35
